UNITED STATES PATENT OFFICE.

HARRY A. SHIELDS, OF GRAND RAPIDS, MICHIGAN, ASSIGNOR TO FREDERICK C. GENGE, OF CHICAGO, ILLINOIS.

FILLING MACHINE.

Application filed March 21, 1921. Serial No. 454,093.

To all whom it may concern:

Be it known that I, HARRY A. SHIELDS, a citizen of the United States, residing at Grand Rapids, in the county of Kent and

5 State of Michigan, have invented certain new and useful Improvements in Filling Machines, of which the following is a specification, reference being had to the accompanying drawings, and to the reference 10 characters marked thereon, which form a part of this specification.

This invention relates to improvements in machines for filling containers with springs, and more particularly for filling fabric 15 pockets with springs under tension, and with holding the pocket containing the compressed or snubbed spring during the operation of closing or sewing the open or free end of the pocket; such spring contained 20 pockets being of the character illustrated and described in the patent to James Marshall, No. 685,160, dated October 22, 1901.

The principal object of my invention is to improve upon the type of machine described and claimed in Letters Patent of the 25 United States No. 1,370,533, dated and issued on the 8th day of March, 1921, to Fredrick C. Genge, and to which reference is hereby made.

30 The present invention improves upon the type of machine referred to, in various details and consists in the devices and combination of devices herein illustrated and described and more particularly pointed out 35 in the appended claims.

The machine, in general terms, comprises a plurality of tubular receptacles, into which springs are placed. These tubular receptacles are generally arranged side by side 40 in a series, in the same plane. Over one end of each of these receptacles are placed a series of flexible pockets or cotton cloth or similar fabric, one end of each pocket being closed. The springs are then forced 45 from the receptacles into the pockets and snubbed or compressed therein, the closed end of the pocket resting against a suitable abutment in what is called a holder. The holder is removable and is so arranged as to 50 retain the springs under compression within the several pockets, until the open or receiving ends of the pockets are suitably closed, when the spring contained pockets are removed and the operation is repeated.

The nature of the invention will be more 55 fully comprehended from the accompanying drawings and subjoined description thereof.

In said drawings:

Fig. 1 is a top or plan view of a filling 60 machine, embracing my invention.

Fig. 2 is an elevation of the upper part of one side of the machine.

Fig. 3 is a vertical sectional view, enlarged, of the upper part of the machine, 65 showing one of the tubular members, and with a spring about to be placed therein,—the view being taken in the plane indicated by the dotted line 3—3 of Fig. 1.

Fig. 4 is a similar view taken on the same 70 plane, showing the spring being moved longitudinally through the tubular member in the direction of the end over which the fabric pocket to be filled may be placed.

Fig. 5 is an elevation of the inside of one 75 of the side members of the machine, showing the piston or plunger operating means.

Figs. 6 and 7 are views in elevation showing the means for shifting the hinged rear 80 part of the tubular spring receptacle from one to the other of its two positions.

Fig. 8 is a side view of the foot lever and connections for operating the work holding box.

Fig. 9 is a plan view of the adjustable 85 foot lever.

Fig. 10 is a horizontal sectional view of the machine frame, without the foot lever, taken in the plane of the dotted line 10—10 of Fig. 11.

Fig. 11 is a rear elevation of a part of the 90 frame.

Fig. 12 is a perspective view further illustrating the plunger operating means.

Fig. 13 is a vertical sectional view, enlarged, showing the plunger in its completed position, with the work holder closed about the fabric pocket and its enclosed 95 spring.

Fig. 14 is a view in perspective, looking 100 toward the face of the work-holder.

Fig. 15 is a vertical, sectional view, also enlarged, of the end plunger of the series, showing its connection with a reciprocating rack.

Fig. 16 is an end view, partially broken away, of one of the plungers.

Fig. 17 is a diagrammatic view indicating

the cross sectional contour of a part of the inclined spring feed table, as viewed in the plane of the line I—I of Fig. 1.

Fig. 18 is a diagrammatic view, taken in the plane of the line II—II of Fig. 1, indicating the cross-sectional contour of the hinged part of two of the tubular members.

Fig. 19 is a diagrammatic view, taken in the plane of the line III—III of Fig. 3, showing the plunger in one of the tubular receptacles, with the hinged part of the latter closed down.

A standard or frame of any convenient construction may be used. In this instance, I illustrate in the drawings, a pair of front uprights or supports 1, 1, and a similar pair of rear supports 2, 2. The front and rear supports are joined by transverse brace bars or tubes, 3, 3, secured in brackets 4, 4. At the top, each front and rear support 1 and 2, on each end of the frame, support and are secured to a side plate or member 5, 5. The two front supports 11 are joined together by a brace rod or tubular member 6, supported on brackets or bearings 7, while the two rear supports 2, 2, are similarly joined by a brace or tubular bar 8, secured in brackets 9, 9. Preferably, the bars 6 and 8 are higher from the floor or other point of support, than are the brace rods or bars 3, 3.

Any suitable power to drive the machine may be used. In the drawing, the power is indicated as a whole, by the letter P, applied to the pulleys mounted on the shaft 10, one end of which shaft may be supported in a suitable journal 11, upon one of the cross bars 3. Attached to one of the side plates 5 and supported upon a shaft 12, 40 is a suitable power transmitting device, including a clutch mechanism. This device is indicated as a whole by the letter B, and it is adapted to be actuated from the power transmitting device P, by any suitable 45 means. One end of this shaft 12 is mounted in the bracket 13, secured to the side plate 5. The details of the power transmitting means and of the clutch mechanism form no specific part of the invention, are not illustrated, and need not be described, since any well known power transmitting and clutch reversing mechanism may be used. The clutch operating mechanism may be actuated in any suitable manner from a shaft 55 14, suitably supported at one end in a bracket 15 mounted upon the frame.

At the forward end of each of the side plate members 5 is a bracket 16, adjustably secured by a bolt 18 passing through the slot 19. These brackets 16 provide at their outer ends, journal bearings 20 for supporting the shaft 21, which latter extends across the front of the machine from one side plate 5 to the other. Hingedly supported 65 upon the shaft 21 is a table 22, provided

at its inner end with a friction or yielding flange 23. The table 22 is located between the ends of the shaft 21, and is provided with a pair of downwardly projecting lugs 24. Between these lugs, a rod 25 is pivotally secured at its upper end.

26, 26 are bearings for supporting the shaft 27, upon which shaft is fulcrumed the foot or operating treadle 28, the arms 29 of which extend over and fulcrum upon the shaft 27. To the rearward end of one of the arms 29, the lower end of the rod 25 is secured. 30 is a spring surrounding the lower end of the arm 25. The spring is held by a pin 31 against upward movement upon the arm 25. 32 is a plate provided with forwardly projecting arms 33, 33, by which the plate 32 is pivotally mounted upon the shaft 27. 34 is an adjusting bolt on the plate 32, one end depending below the plate 32 and in juxtaposition to bear against the top surface of the arm 29 of the treadle 28. When foot pressure is applied to the treadle 28, the spring 30 is first compressed, and then the rod 25 moved upwardly and as the treadle 28 continues to rock about the shaft 27, one of its arms 29 strikes the bolt 34 and carries the plate 32 upwardly with a rocking movement about the shaft 27. The plate 32 is also a foot treadle and has a rearwardly extending arm 35, to the outer end of which a connecting rod 36 is joined, the upper end of this connecting rod being suitably connected to a crank arm 37 on the operating shaft 13.

Upon the top of the frame, at the rear thereof, and joining the two side plates 5, 5, is a flat table indicated by the letter T. This is preferably made of wood, as indicated. Between the forward margin of this table T and the transverse shaft 21, are a pair of supporting and connecting bars 38, 38, the same being preferably of channel iron. These extend from one side plate 5 to the other. Upon these supporting bars 38 is mounted a plurality of pocket filling cylinders, of peculiar construction, and designated as a whole by the letter C. These cylinders, preferably of sheet metal, are placed side by side, and the group extends from one side plate 5 to the other. The springs S are fed into the cylinders and moved longitudinally therethrough by pistons or plungers 39. The forward end of the tube C is provided with a hinged cover 40 having an inclined upper surface. This cover is so constructed that when closed, as shown in Fig. 3, the forward end of the tube C is substantially closed and is of such cross-sectional area as to permit the open ended fabric pocket F to be readily placed thereover. When the plunger 39 is being actuated in its forward movement, to press the spring S through the tube C, the forward end of said moving spring readily 130

raises the hinged cover 40 into the position shown in Fig. 4, thus distending the open mouth of the fabric pockets and holding the pocket upon the cylinder by frictional contact, the pocket being then in tubular form, ready to receive the spring S.

In the rear of the tubes C, I place a spring feeding table, indicated as a whole by the letter D, the same consisting of a plurality 10 of U-shaped troughs, one for each cylinder, the shape of each being clearly shown in Fig. 17. The end trough of the series is provided with an L-shaped bracket support 41, by which said feed table D may be supported upon the side plates 5, 5. It will be noted by reference to Figs. 3 and 4 that the work receiving table T has a horizontal surface, while the surface of the feed table D is inclined forwardly and downwardly. 15 The springs S are brought in quantities to the table T. The operator then places the springs in the grooves or recesses of the inclined feed table D, where the end of each spring will rest against a back stop 42. 20 When the plunger 39 is in operation, as indicated in Fig. 3, the springs S are prevented from sliding down from the feed table D into the tube C, by the back stop 42, which is mounted on the swinging top E, the 25 cross sectional shape of which tubes C are indicated in the view, Fig. 18. The top E consists in a plurality of sheet metal members hinged at their forward ends, at 43, 43, to the tube C, and all joined at their forward 30 ends by the L-shaped transverse bar 44. When the tops E are in their lower position, as indicated in Fig. 3, they complete the tubes C and form substantially a cylinder through which the springs S and the plungers 39 move. This is more particularly indicated in Figs. 3 and 19. It will be understood that the tops E, being connected to the bar 44, will all move in unison. This movement may be accomplished by the following 35 means:

On each of the side plates 5 is a bearing 45 for a stub shaft or pin 46. On each pin 46 is mounted a lifting arm 47. The longer end of the arm 47 is provided with a shoulder or bearing flange 48, resting in contact with the under surface of the L-shaped transverse bar 44. It will be noticed by Figs. 6 and 7 that when the short arm 49 is in its forward position, the flange 48 on 50 the longer arm is in its lowest position, thus permitting the top E to swing downwardly by gravity into the position shown in Figs. 4, 6 and 19. In this position, the stop 42 closes off the forward end of the complementary grooves or spring-holding runways in the receiving table D, thus preventing the springs from slipping off the table D into the tube C. It will also be noticed that when the short arm 49 is in its rear position, 55 as indicated in Fig. 7, the swinging top E is

raised, as clearly shown in Figs. 3 and 7, thus permitting the springs S to slide from the receiving table D under the rearward or swinging end of the top E and into the cylinders C.

Means for actuating the levers 47 comprise rods 50, 50, the forward end of which is operatively connected with the short arm 49 of the lever 47, while the rearward end is passed through a suitable aperture in a channel bar 51, and is provided with a shoulder, in this case the nut 52, adapted to be engaged by said channel bar 51. This channel bar 51 extends transversely of the machine, and is the bar to which the rear ends 75 of the plunger rods 53 are all attached. The two ends of the channel bar 51 move in guideways extending in a direction from front to rear of the machine, which guideways are formed by parallel flanges 54, extending from the inside of the side plates 5, whereby the bar 51 is adapted to reciprocate forward and back in guideways. The bar 51 is actuated by means of a pair of plunger rods 55 having on their lower faces gear 80 teeth 56. These plunger rods 55 are preferably the end bars of the series of rods 53, each bar 55 carrying at its forward end one of the plungers 39.

Transversely of the machine is a rotatable 85 shaft 57 carrying a pair of pinions 58, each of the two pinions being placed upon the shaft 57 in such position as to engage the teeth 56 of one of the rack bars 55. It follows that when the shaft 57 is rotated, the 90 rack bars 55 are moved forward or backward as the case may be. The channel bar 51 to which they are secured being similarly reciprocated, and all of the plungers 39 are actuated simultaneously.

Motion may be communicated to the shaft 57 through a gear wheel 59 mounted on said shaft, and in mesh with a spur pinion 60, located upon the shaft 12.

In operation, a plurality of fabric pockets 110 F, closed at one end, are presented with their open ends opposite the forward ends of the series of pockets C, the latter being in the position shown in Figs. 2 and 3. The open ends of the fabric pockets are then drawn 115 over and upon the tubes C. Springs S being in the troughs of the feed table D, slide quickly into the cylinders as soon as the top E is raised. The plungers 39 are started on their forward or spring compression stroke. The series of swinging tops E being lowered as shown in Fig. 3, the forward movement of the plungers is continued until said springs raise the hinged top 40 of the tubes C, thereby distending and holding the open mouths of the pockets firmly to the cylinder tube ends. The plungers 39 continuing their forward movement, force the springs into the pockets and compress 120 them therein as shown more clearly in Fig. 130

13. The operator then depresses the treadle 28 with the result that the pocket holders, about to be described, operate and open and receive the major portion of the spring filled pocket. Upon the release of the treadle, the pocket holder parts close down upon the spring filled fabric at a point in rear of the forward end of the plungers, as clearly shown in Fig. 13. Then the plungers are 10 withdrawn. This withdrawal of the plungers by means of the bodily moving of the channel bar 51 likewise actuates the arms 47, 49, to which the channel bars are secured, and raises the tops E again into the 15 position shown in Fig. 3; thus permitting the springs S to start to feed by gravity from the feed table D into the tubes C, and thereupon the operation is repeated.

The construction of the fabric holder and 20 the means for permitting the action just described with respect thereto, is as follows:

The holder H is an elongated metallic box made in two halves, hinged together at 61, each half comprising a front wall 62, an 25 inturned rear wall and a connecting wall 64. It will be observed that the walls are parallel to the rear walls 62 but are not so deep, the wall 62 being so constructed as to form the hinge 61. The halves of the holder 30 thus open out like jaws. The holder is of a length equal to the width of the series of tubes C. The adjacent forward margins of the rear, inturned wall are provided with a plurality of lugs 65, with intervening recesses, as clearly shown in Fig. 14. Each 35 of the lugs 65 registers with a complementary, longitudinally arranged groove 66 in the plungers 39. These grooves are shown more completely in Figs. 13, 15 and 16. I have 40 indicated in Fig. 13, the fabric pocket by the letter F. When the halves of the holder H are opened in the position shown in Fig. 3, the closed end of the pockets F containing the spring, are moved in between the 45 jaws of the holder H, and just as the plunger 39 reaches its forward movement, the treadle 28 is released, and thereupon the two halves of the holder H are brought together and closed about the spring filled fabric pocket.

50 The lugs 65 bear against the fabric of the pockets and guide them into the recesses 66. As the plunger 39 withdraws to the rear of the machine, away from the pockets, the springs S therein expand, somewhat, but 55 the expansion movement is limited by the fact that the last volute of the spring presses the fabric of the pocket against the inside of the forward walls 63 of the holder H. Further recession of the plunger 39 and the 60 dropping down of the hinged top 40 of the cylinder, completely frees the open end of the pocket fabric from the cylinder. The holder H, as a whole, with the spring contained pockets thus held therein, may be 65 removed from the machine and the pocket

ends closed by sewing or other means, while the spring is still compressed. While the pockets are being closed, a new, unfilled holder H may be placed in position upon the table 22, and the operation repeated.

70 While modifications may be made in many of the details of the devices described as embodying the present invention, and the forms herein illustrated are recommended as very desirable, based upon successful operation and use,—nevertheless, I would not have my invention limited to the specific details herein shown and described except as set forth in the appended claims.

75 I claim as my invention:

1. In a machine for filling fabric pockets with springs, a cylinder having a part of its receiving end cut away, a movable cover for said cut-away part, the discharge end of the cylinder being adapted to sustain the 85 fabric pocket, a spring supporting table inclined toward the receiving end of the cylinder, an abutment on said movable cover to normally hold a spring from moving from the inclined table into a cylinder, and means 90 for raising the abutment to permit the spring to slide into the cylinder.

2. In a machine for filling fabric pockets with springs, a cylinder having a part of its receiving end cut away, a movable cover for 95 said cut-away part, the discharge end of the cylinder being adapted to sustain the fabric pocket, a spring supporting table inclined toward the receiving end of the cylinder, a spring retaining abutment on said movable 100 cover and means for actuating the movable cover to release the spring.

3. In a machine for filling fabric pockets with springs, a cylinder having a part of its receiving end cut away, a movable cover for said cut-away part, the discharge end of the cylinder being adapted to sustain the fabric pocket, a spring supporting table inclined toward the receiving end of the cylinder, an abutment on said movable cover 105 to normally block the movement of a spring from the table into a cylinder, means for actuating the movable cover, and means in the cylinder for ejecting the spring and forcing it under compression into the 110 pocket.

4. In a machine for filling fabric pockets with springs, a plurality of cylinders lying side by side, each cylinder having a spring receiving and a spring discharge end, the 115 latter being adapted for cooperative engagement with the fabric pocket to be filled, a movable cover for the receiving end of the cylinder, an abutment on said cover, against which a spring will rest when the cover is 120 down, a spring supporting table having troughs for individual springs, each aligned with a cylinder and the table being inclined downwardly towards the receiving end of the cylinders, and means for lifting the 125 130

abutments simultaneously to permit the springs to slide from the table into their respective cylinders.

5. In a machine for filling fabric pockets with springs, a plurality of cylinders lying side by side, each cylinder having a spring receiving and a spring discharge end, the latter being adapted for cooperative engagement with the fabric pocket to be filled, 50
- 10 a movable cover for the receiving end of the cylinder, an abutment on said cover, against which a spring will rest when the cover is in its normally closed position, a spring supporting table having troughs for individual 55
- 15 springs, each aligned with a cylinder and the table being inclined downwardly towards the receiving end of the cylinders, and means for actuating the abutments to permit the springs to enter the cylinders. 60
- 20 6. In a machine for filling fabric pockets with springs under tension, a spring holding inclined table, a movable abutment in the path of movement of the spring, a cylinder adapted to receive the spring when the 65
- 25 abutment is raised, a reciprocating plunger in the cylinder, a hinged closure for the discharge end of the cylinder shaped to permit a fabric pocket to be placed thereover, an abutment adjacent to the discharge end of 70
- 30 the cylinder, means for forcing the spring through the cylinder and into the pocket and for compressing the spring within the pocket, a removable pocket holder including 75
- 35 said last mentioned abutment, and means for retaining the pocket in said holder with the spring under compression with the open end of the pocket projecting from the holder. 80
7. In a machine for filling fabric pockets with springs under tension, a spring holding 85
- 40 inclined table, a movable abutment in the path of movement of the spring, a cylinder adapted to receive the spring when the abutment is raised, a reciprocating plunger in the cylinder, a hinged closure for the 90
- 45 discharge end of the cylinder shaped to permit a fabric pocket to be placed thereover, an abutment adjacent to the discharge end of the cylinder, means for forcing the spring through the cylinder and into the pocket and 95
- 50 for compressing the spring within the pocket, a removable pocket holder including said last mentioned abutment, and means for retaining the pocket in said holder with the spring under compression with the open 100
- 55 end of the pocket projecting from the holder, and means for raising the free end of the first mentioned abutment out of the path of the spring to permit the latter to slide from its holding table into the cylinder. 105
- 60 8. In a machine for filling fabric pockets with springs, a plurality of cylinders lying side by side, each cylinder having a spring receiving and a spring discharge end, the latter being adapted for cooperative engagement with the fabric pocket to be filled, a 110
- 65

movable cover for the receiving end of each cylinder, a spring supporting table having troughs for individual springs, each aligned with a cylinder and the table being inclined downwardly towards the receiving end of the cylinders, a back stop or abutment on each movable cover to normally retain the spring on said inclined table, and means for actuating the abutments to permit the springs to enter the cylinders, said actuating means including plunger rods and pivoted levers, one end of which contacts with the series of abutments, the other end being connected with and actuated by the plunger- 75

rods. 80

9. In a machine of the class described, a cylinder adapted to contain a spring, a plunger therein adapted to eject the spring and force it and its container into a work holder, the exit end of the cylinder being 85

adapted to sustain and support a spring container and being provided with a movable part adapted to expand the mouth of the container, a support, a removable two-part work holder on the support, the back 90

of the holder constituting an abutment to cooperate with the plunger to compress the spring, means for spreading the holder apart to receive the spring filled container 95

and means on the holder for holding the container and its spring within said holder when the plunger is withdrawn. 100

10. In a machine of the class described, a cylinder adapted to contain a spring, a plunger therein adapted to eject the spring 100

and force it and its container into a work holder, the exit end of the cylinder being adapted to sustain and support a spring container and being provided with a movable part adapted to expand the mouth of the container, a support, a removable two-part work holder on the support, the back 105

of the holder constituting an abutment co-operating with the plunger to compress the spring, means for spreading the holder apart to receive the spring filled container and means on the holder for holding the container and its spring within said holder when the plunger is withdrawn, the two 110

parts of the holder being hinged together 115

on one side.

11. In a machine of the class described, a cylinder adapted to contain a spring, a plunger therein adapted to eject the spring and force it and its container into a work 120

holder, the exit end of the cylinder being adapted to sustain and support a spring container, and being provided with a movable part adapted to expand the height of the container to receive the spring, a support, a removable two-part work holder on the support, one wall of the holder constituting an abutment co-operating when the holder is open with the plunger to compress the spring forced from the cylinder into the 125

130

holder, means for spreading the holder apart to receive the spring filled container, means on the holder for retaining the container and its spring within the holder when 5 the plunger is withdrawn, the proximate edges of the walls of the two-part holder on the side next to the plunger being spaced apart a distance less than the diameter of the plunger, and complementary means on 10 the plunger to permit its forward end to enter the holder when the latter is closed.

12. In a machine of the class described, a cylinder adapted to contain a spring, a plunger therein adapted to eject the spring and 15 force it and its container into a work holder, the exit end of the cylinder being adapted to sustain and support a spring container and being provided with a movable part adapted to expand the mouth of the container, a support, a removable two-part 20 work holder on the support provided with inwardly turned lugs on the adjacent walls thereof, the back of the holder constituting an abutment cooperating with the plunger, 25 when the holder is open, to compress the spring, means for spreading the holder apart to receive the spring filled container and means on the holder for holding the container and its spring within said holder 30 when the plunger is withdrawn, the plunger being provided with diametrically opposite grooves extending longitudinally from its front end, said lugs being adapted to enter the plunger grooves when the plunger is 35 forcing the spring filled container into the holder.

13. In a machine of the class described, a cylinder adapted to contain a spring, a plunger therein adapted to eject the spring and 40 force it and its container into a work holder, the exit end of the cylinder being adapted to sustain and support a spring container and being provided with a movable part adapted to expand the mouth of the container, a support, a removable two-part 45 work holder on the support, the back of the holder constituting an abutment which when the holder is open to receive the spring, cooperates with the plunger to compress the spring, 50 means for spreading the holder apart to receive the spring filled container and means on the holder for holding the container and its spring within said holder when the plunger is withdrawn, the plunger being provided with diametrically opposite grooves 55 extending longitudinally from its front end, and the inwardly turned lugs on the adjacent walls of the holder adapted to enter the plunger grooves when the plunger is 60 forcing the spring filled container into the holder, the distance between the said lugs when the holder is closed about the spring filled container being somewhat less than the diameter of the spring.

65 14. In a machine of the class described, a

cylinder adapted to contain a spring, a plunger therein adapted to eject the spring and force it and its container into a work holder, the exit end of the cylinder being adapted to sustain and support a spring 70 container and being provided with a movable part adapted to expand the mouth of the container, a support, a removable two-part work holder on the support, the back of the holder constituting an abutment which when 75 the holder is open to receive the spring, cooperates with the plunger to compress the spring, means for spreading the holder apart to receive the spring filled container and means on the holder for holding the container and its spring within said holder when the plunger is withdrawn, the work holder being long enough to extend across a plurality of said cylinders placed side by side and adapted to receive the spring filled containers from all of the cylinders simultaneously.

15. In a machine of the class described, a cylinder adapted to contain a spring, a plunger therein adapted to eject the spring and 80 force it and its container into a work holder, the exit end of the cylinder being adapted to sustain and support a spring container and being provided with a movable part adapted to expand the mouth of the container, a support, a removable two-part 85 work holder on the support, the back of the holder constituting an abutment which when the holder is open to receive the spring, cooperates with the plunger to compress the 90 spring, means for spreading the holder apart to receive the spring filled container and means on the holder for holding the container and its spring within said holder when the plunger is withdrawn, said holder spreading means including a foot treadle and operative connections between it and the 95 holder.

16. A machine of the class described, embracing means for filling a plurality of containers each with a spring, means for moving the containers into a work holder, and actuating mechanism for each of said means, combined with a treadle device operatively connected with each of said actuating mechanisms, said treadle device having means for synchronizing the movement of the actuating mechanisms.

17. In a machine of the class described, embracing means for filling a container with a spring, means for holding the spring filled container, and actuating mechanisms for each of said means, a treadle device operatively connected with each of said actuating mechanisms, said treadle device having means for starting one of the actuating mechanisms ahead of the other.

18. In a machine of the class described, embracing means for filling a container with a spring, means for holding the spring filled

container, and actuating mechanisms for each of said means, a treadle device operatively connected with each of said actuating mechanisms, the movement of the treadle 5 starting one of said actuating means and the further or continued movement of the treadle starting the other actuating mechanisms.

19. In a machine of the class described, embracing means for filling a container with 10 a spring, means for holding the spring filled container, and actuating mechanisms for each of said means, a treadle device operatively connected with each of said actuating mechanisms, said treadle device comprising 15 a shaft, a foot treadle fulcrumed thereon and operatively connected with one of the actuating mechanisms, and a second treadle member fulcrumed on said shaft and operatively connected with the other actuating 20 mechanism and means for rocking the second treadle member by the movement of the other treadle member.

20. In a machine of the class described, embracing means for filling a container with

a spring, means for holding the spring filled 25 container, and actuating mechanisms for each of said means, a treadle device operatively connected with each of said actuating mechanisms, said treadle device comprising a shaft, a foot treadle fulcrumed thereon and 30 operatively connected with one of the actuating mechanisms, and a second treadle member fulcrumed on said shaft and operatively connected with the other actuating 35 mechanism and means for rocking the second treadle member, said last mentioned means including a depending bolt adjustably mounted in the second treadle member.

In testimony, that I, claim the foregoing 40 as my invention I affix my signature, in the presence of two witnesses, this 16 day of March, 1921.

HARRY A. SHIELDS.
